COMBINATION DRINKING GLASS AND
TOOTH BRUSH HOLDER

Fred Uttley, Edgewood, R. I.

Application April 28, 1934, Serial No. 722,841

5 Claims. (Cl. 312—112.5)

This invention is a holder for placing glasses in an inverted position, thereby insuring a glass being dry and free from fly dirt or other foreign substances.

5 It is well understood by the public that drinking glasses when placed in one of the old type holders retain the drainings of whatever has been placed in them by the user, said glass and its contents making a very good drinking place or breeding place for flies, mosquitoes, and other disease carrying insects.

This new type holder is so made as to also take care of tooth brushes in a sanitary manner; brushes may be seen in any home placed in hooks, 15 or laid on a tray where flies or other vermin can walk all over said brushes besides being exposed to any dust that may blow in through open windows or when cleaning rooms where brushes are kept.

20 This invention is a sheet metal stamping that holds a glass in an inverted position and also provides a clean resting place for four tooth brushes, as illustrated in the enclosed drawing, and will provide sanitary protection at such a low price as to protect the poor as well as the rich, 25 from the contamination of unsanitary drinking glasses or tooth brushes.

A further object of my invention is to provide 30 a device of the above description so constructed that the brush ends of the tooth brushes or upper ends of the other small articles employed may be inserted and removed from their supporting shelf without removal of the inverted glass tumbler.

35 A further object of my invention is to provide a detachable article holding shelf, which may if desired, be cut or formed from the sheet material of the central support and a further object of my invention therefore is to provide an article of this description which may be fabricated in a simple manner from sheet material.

These and such other objects of my invention as may hereinafter appear will be best understood 45 from a description of the accompanying drawing forming a part thereof.

In the drawing, Fig. 1 is a side elevation of my improved combination glass tumbler and small article support mounted on a wall surface and 50 showing an inverted glass tumbler mounted thereon in section and tooth brushes removably mounted thereon shown in dotted lines.

Fig. 2 is a front view thereof with the inverted glass tumbler and tooth brushes removed.

55 Fig. 3 is a plan view of the parts shown in Fig. 1.

Fig. 4 is a perspective view of the specific type of detachable shelf I preferably employ.

In the drawing, wherein like characters of reference indicate like parts throughout, 10 generally indicates a combination glass tumbler and small article support.

In my preferred embodiment said device is constructed of flat sheet material and includes a flat central supporting sheet 18 having an extension 12 projecting substantially at right angles from the lower end thereof provided with suitable means 14 for attachment thereof to a vertical surface such as the wall surface 16 shown in Figs. 1 and 2 for vertical mounting of the central supporting sheet 18. In my preferred embodiment 15 said means 14 comprises the extensions 14 bent at right angles on the inner end of said extension 12 and provided with central screw holes 20 to receive the screws for securing said extensions 14 to the wall surface 16. In my preferred embodiment 20 the upper edge of said extension 12 is provided with a glass tumbler edge guide supporting slot 24. The central supporting sheet 18 is provided with a horizontal slot 26 substantially centrally thereof. I also provide an upper flat 25 shelf or means 28 preferably constructed of light material having the center portion thereof secured by solder or otherwise to the upper end of said supporting sheet 18 to provide means on the upper end of said central support 18 for abutting the side walls of an inverted glass tumbler 30 to retain it in an inverted vertical position thereon with the lower edge of said side wall supported in said slot 24.

I also provide a preferably detachable shelf 36 35 preferably as shown in Fig. 1 cut out from the upper portion of the central supporting sheet 18 to save metal shaped to be detachably mounted in said slot 26 and having tooth brush or small article holding means 38 therein, in my preferred embodiment comprising the notches 38. Said shelf 36 is preferably provided with the extensions 40 on one side of the central line thereof to prevent the detachable shelf 36 from completely sliding through the horizontal slot 26.

Said shelf 36 and notches 38 are of such a size that the brush ends 42 of the tooth brushes 44 or upper ends of other small articles employed may be as shown in Figs. 1 and 2 inserted in and removed from said notches 38 while the inverted tumbler 30 is in mounted position on my improved support.

It is apparent that I have provided a novel type of glass tumbler and small article support adapted to receive the glass tumbler in inverted posi-

tion thereon as a cover for the toothbrushes mounted centrally therein, permitting the water to discharge downwards along the inner surface of the wall 32 of the tumbler away from the tooth brushes 44 mounted centrally therein and permitting the toothbrushes to be inserted and removed from their supporting notches 38 while the inverted tumbler is in mounted position on said support.

10 It is understood that my invention is not limited to the specific embodiment shown and that various deviations may be made therefrom without departing from the spirit and scope of the appended claims.

15 What I claim is:

1. A combination glass tumbler and small article support, constructed of flat sheet material, comprising a central supporting sheet having an extension projecting substantially at right angles 20 from the lower end thereof having means thereon for attachment to a vertical surface for vertical mounting of said central supporting sheet, said extension having a tumbler edge supporting slot therein, said central sheet having a horizontal 25 slot substantially centrally thereof and means on the upper end thereof for abutting the side wall of an inverted glass tumbler to retain it in a vertical position thereon with the lower edge thereof supported in said supporting slot and a detachable shelf cut from said central supporting sheet shaped to be detachably mounted in said slot having tooth brush or other small article holding notches therein, said shelf and notches being of such a size that the brush ends of said toothbrushes or upper ends of said small articles may be inserted in and removed from said notches while the inverted tumbler is in mounted position thereon.

2. A combination glass tumbler and small 40 article support, comprising a support having a horizontal slot substantially centrally thereof, means thereon for supporting the lower end of an inverted glass tumbler and means on the upper end thereof for abutting the side walls of 45 said inverted tumbler to retain it in vertical position thereon and a detachable shelf shaped to be detachably mounted in said slot having toothbrush or other small article holding notches therein, said shelf and notches being of such a size that the brush ends of said toothbrushes or upper ends of said small articles may be inserted in and removed from said notches while the inverted tumbler is in mounted position thereon.

3. A combination glass tumbler and small article support, comprising, a central support having means for supporting a tumbler in inverted vertical position thereon and a diamond shaped shelf mounted on said support within said tumbler at a spaced distance below the upper end of said support projecting radially from said central support member and terminating at its obtuse angle ends a substantial distance from the wall of said inverted glass having toothbrush or other small article holding notches therein, said shelf and notches being of such a size that the brush ends of said toothbrushes or upper ends of said small articles may be inserted in and removed from said notches while the inverted tumbler is in mounted position thereon.

4. A combination glass tumbler and small article support, comprising a central support having means for supporting a tumbler in inverted vertical position thereon and a diamond shaped shelf mounted on said support at a spaced distance below the upper end of said support projecting radially from said central support member and terminating at its obtuse angle ends a substantial distance from the wall of said inverted glass having toothbrush or other small article holding means therein, said shelf and means being of such a size that the brush ends of said toothbrushes or upper ends of said small articles may be inserted in and removed from said means while the inverted tumbler is in mounted position thereon.

5. A combination glass tumbler and small article support, comprising, a vertically central member, means attached thereto for supporting the lower edge of a tumbler in inverted position over said member, means thereon for abutting the side walls of said inverted tumbler to retain it in inverted position thereon and a diamond shaped shelf mounted on said member within said tumbler at a spaced distance below the upper end of said member projecting radially from said central support member and terminating at its obtuse angle ends a substantial distance from the wall of said inverted glass having toothbrush or other small article holding notches therein, said shelf and notches being of such a size that the brush ends of said toothbrushes or upper ends of said small articles may be inserted in and removed from said notches while the inverted tumbler is in mounted position.

FRED UTTLEY.
